Des. 208,547
Patented Sept. 12, 1967

208,547

HEAT SINK

Robert G. Van Houten, Grand Junction, Colo., assignor
to Delta Products, Inc., Grand Junction, Colo., a cor-
poration of Colorado

Filed Mar. 9, 1965, Ser. No. 84,166

Term of patent 14 years

(Cl. D26—1)

FIG. 2.

FIG. 3.

FIG. 1.

FIG. 4.

FIG. 1 is an end elevational view of a heat sink, showing my new design, the opposite end being a mirror image thereof;

FIGURE 2 is a top plan view;

FIGURE 3 is a fragmentary side elevational view, the opposite side being a mirror image thereof, a portion having been broken away for convenience in illustration; and

FIGURE 4 is a cross-sectional view partly in side elevation, taken on line 4—4 in FIGURE 1.

I claim:

The ornamental design for heat sink, as shown and described.
